DESIGN FOR A HANDCART OR SIMILAR ARTICLE

Albert L. Wadley, New Market, N. J.

Application March 19, 1942, Serial No. 106,248

Term of patent 3½ years

To all whom it may concern:

Be it known that I, Albert L. Wadley, a citizen of the United States, residing at New Market, in the county of Middlesex and State of New Jersey, have invented a new, original, and ornamental Design for a Handcart or Similar Article, of which the following is a specification, reference being had to the accompanying drawing, forming part thereof.

Figure 1 is a top perspective view of a handcart or similar article showing my new design,

I claim:

The ornamental design for a handcart or similar article, as shown.

ALBERT L. WADLEY.
